(57) **CLAIM**

The ornamental design for a toy fishing rod and reel, as shown and described.

DESCRIPTION

FIG. 1 is a rear, left perspective view of a toy fishing rod and reel showing the new design;

FIG. 2 is a front, left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dashed lines shown in the drawings illustrate portions of the toy fishing rod and reel that form no part of the claimed design.
